CLAIM

The ornamental design for a pressurized air delivery console, as shown and described.

DESCRIPTION

FIG. 1 is a front perspective view of a pressurized air delivery console showing our new ornamental design;

FIG. 2 is a front view thereof;

FIG. 3 is a top view thereof;

FIG. 4 is a bottom view thereof;

FIG. 5 is a right side view thereof;

FIG. 6 is a left side view thereof; and,

FIG. 7 is yet another front perspective view thereof.

The broken lines represent environmental structure or unclaimed portions of the pressurized air delivery console and do not form a portion of the claimed design.
